UNITED STATES PATENT OFFICE.

WILLIAM ORD, OF BROOKLYN, OHIO.

BOILER-CLEANING APPARATUS.

SPECIFICATION forming part of Letters Patent No. 311,672, dated February 3, 1885.

Application filed July 21, 1884. (No model.)

To all whom it may concern:

Be it known that I, WILLIAM ORD, of Brooklyn, in the county of Cuyahoga and State of Ohio, have invented certain new and useful 5 Improvements in Boiler-Cleaning Apparatus; and I do hereby declare the following to be a full, clear, and exact description of the invention, such as will enable others skilled in the art to which it pertains to make and use the 10 same:

My invention relates to apparatus for cleaning steam-boilers, the object being to provide a scraping device for removing sediment and scales from the inside or the bottom of the 15 boiler when a pressure of steam is on the boiler. A further object is to provide a removable rod for operating the scraper, and arranged to operate through a stuffing-box, so that no leakage is had in operating the device. A further 20 object is to provide a hollow bolt for the hand-hole plate, through which the scraper-rod may pass into the boiler. A further object is to provide a tilting scraper that will tilt or turn, so as to slide on the surface when drawn in 25 one direction, but will assume an upright position and scrape the surface when drawn in the opposite direction. A further object is to provide a reversible scraper that may be made to remove the sediment in either direction, to 30 the end that the sediment is moved toward the blow-off pipe. A further object is to provide a seat on the inside of the man-hole plate and around the opening through which the scraper-rod passes, and a corresponding plug 35 on either side of the scraper, into which the scraper-rod is screwed, and so arranged that when the plug is drawn within the said seat it prevents leakage from the boiler when the 40 scraper-rod is removed.

With these objects in view my invention consists in certain features of construction and in combination of parts, hereinafter described, and pointed out in the claims.

In the accompanying drawings, Figure 1 is 45 a longitudinal vertical section of a boiler and my improved cleaning apparatus in position. Fig. 2 is an enlarged view in perspective of the scraper in an upright position. Fig. 3 is an enlarged view in perspective of the scraper 50 in a tilted position. Fig. 4 is an enlarged longitudinal section of the scraper and the boiler

attachments through which the scraper operates. Fig. 5 is a longitudinal section of the hollow bolt through which the scraper-rod passes.

A represents a steam-boiler provided with the hand-hole plate B, secured in the usual manner by the bolt b and the bridge b'. C is the head or body of the scraper, curved longitudinally to correspond with the boiler, and 60 has a series of ears, c, depending from the lower side, to which are riveted the metal strips C', that form the scraper proper. These sheets are preferably of spring-brass and quite thin and flexible, and curve more less in cross-section, so that when moved in one direction they draw under the scales and sediment, and when moved in the opposite direction will have a tendency to ride over the sediment. These sheets are slitted part way into narrow strips, 65 as shown, so that when one part engages a rivet-head it will spring back and pass over the obstruction, and then return to its place without interfering with the action of the other parts of the scraper. The part C has a depression 70 in the central part extending laterally, and deeper at one edge than at the other. In this depression is pivoted the part D, that is a plug round in cross-section and tapering toward each end. The pocket or depression in 75 the part C is only deep enough on one side at d to admit of the part D when the latter is about parallel with a cross-section of the part C, as shown in Figs. 1, 3, and 4. The depression at d' on the other edge of the part C is deep 80 enough to allow the part C to be tilted in the position shown in Fig. 2, and this tilting of the scraper, together with the curvature of the plates C', causes the scraper, when moved to the left hand, to ride over the sediment without removing it. Each end of the plug D has a central hole, d'', threaded to receive the rod E, by which the scraper is moved. The outside of the plug on each end is fitted to a tapering seat, 85 b'', on the inner end of the hollow bolt b. The hole in the bolt is large enough to admit the passage of the rod E freely, and a pipe, E', is coupled onto the outer end of the bolt and extends through the smoke-box F, and is provided at the outer end with the part e and the gland e', 90 forming a stuffing-box around the rod E. The relation of parts is such that when the rod E is

screwed into one end of the plug D the scraper, when in an upright position, as in Figs. 1 and 3, will rest on the boiler. The rod E is long enough to move the scraper to the back 5 end of the boiler. The scraper arranged as shown in the drawings would move the sediment to the forward end of the boiler, as would be the case if the blow-off were located at the front end. If, however, the blow-off 10 pipe were at the back end of the boiler, the scraper should be reversed and the rod E screwed into the opposite end of the plug D. In this case the scraper would move the sediment rearward, and would slide over the sediment 15 when the scraper was drawn forward.

When it is desired to clean the boiler, the blow-off valve is opened and the scraper drawn forward and back as rapidly as possible for a few moments. The scraper loosens 20 the sediment and moves it toward the blow-off, and the current through the latter quickly removes the sediment from the boiler. Also, in working the scraper rapidly, waves are formed in the boiler that wash the dirt from 25 the lower flues, and aid more or less in cleansing the flues farther up into the boiler. When the scraping is done, the blow-off valve is closed and the scraper is drawn forward. As it approaches the front end, it should be 30 moved rapidly, so that the forward end of the plug D will be drawn into the seat b^2 with some force. The pressure of steam in the rear will of course keep the plug in this position, and the rod E may be unscrewed and re- 35 moved. The rod E, passing through the hollow bolt b , guides the plug D to the seat b^2 , and when the rod is again introduced in the bolt b it in turn is guided to its engagement with the plug D. The scraper may extend 40 more or less around the inner circumference of the boiler, according to the location of the tubes. The scraper should be of such dimensions that it can be inserted in the hand-hole by turning the scraper sidewise; but usually there 45 is ample room for inserting the scraper. When the rod E is removed, this device is entirely out of the way. In case the hand-hole plate is to be removed, it requires but a moment to unscrew the pipe E', and then the hand-hole 50 plate may be removed in the usual manner.

In many localities where it is necessary to use muddy water in boilers this device will be found very useful, as it can be operated at any time with a full head of steam on the boiler. The introduction of the rod E into 55 the boiler is not necessarily confined to the hand-hole plate. If no hand-hole plate is located convenient for the purpose, a hollow plug may be inserted in the head of the boiler that will answer the same purpose of the bolt 60 b , having, of course, a seat, b^2 . In such case the scraper could be inserted through the man-hole or through a hand-hole located at some other part, and when all the parts are in position they can be operated just as described 65 without further trouble.

What I claim is—

1. In a boiler-cleaner, a tilting scraper, pivoted as shown, and located inside of a steam-boiler, and operated by an inflexible rod extending outside of the boiler, substantially as set forth. 70

2. A reversible tilting scraper located inside of the steam-boiler and operated by an inflexible rod extending outside of the boiler, and so 75 arranged that sediment may be scraped toward either end of the boiler, according to the position of the scraper, substantially as set forth.

3. The combination, with a scraper located inside a steam boiler and operated by a rod 80 extending outside of the boiler, of a hollow bolt for securing the hand-hole plate, and so arranged that the hole in the bolt furnishes a passage-way for the scraper-rod, substantially as set forth. 85

4. In a boiler-cleaner, the combination, with the hollow bolt b , provided with an enlarged tapering opening or seat, b^2 , of the part D, adapted to engage the seat b^2 , substantially as set forth. 90

5. In a boiler-cleaner, the combination, with the hollow bolt b , of the tube E' and the parts e and e', substantially as set forth.

In testimony whereof I sign this specification, in the presence of two witnesses, this 9th day of July, 1884. 95

WILLIAM ORD.
